Atty.

United States Patent Office.

ALDEN BRIGHAM, OF COLD BROOK, MASSACHUSETTS.

Letters Patent No. 67,019, dated July 23, 1867.

IMPROVED DUST-PAN.

The Schedule referred to in these Letters Patent and making part of the same.

KNOW ALL MEN BY THESE PRESENTS:

That I, ALDEN BRIGHAM, of Cold Brook, in the county of Worcester, and Commonwealth of Massachusetts, have made certain new and useful Improvements in Dust-Pans; and I do hereby declare that the following is a full, clear, and exact description of the same, reference being had to the accompanying drawings, forming a part of this specification, in which—

Figure 1 represents a perspective view of my improved dust-pan, and

Figure 2 represents a section on line A B, fig. 1.

To enable those skilled in the art to which my invention belongs to make and use the same, I will proceed to describe it more in detail.

The object of my invention is to obviate the necessity of stooping to brush the dirt from the floor or carpet into a dust-pan after it has been swept into a bunch, or so as not to occupy but a small space upon the carpet or floor, and also to facilitate the removal of the dust and dirt from the pan in expeditious and easy manner.

In the drawings, A, fig. 1, represents the pan complete. The bottom B is made wide in front, and gradually tapers as it extends back. The sides C C rise gradually, and also converge towards each other as they extend back until they reach the points *a a*, when they drop or incline down slightly until they reach the points *b b*, where they are combined, or until with the inclined back D, which extends back and up from the bottom B, as fully shown in the drawings, and in combination with the sides C C form a somewhat oval or oblong-shaped opening, E, back of the rail or handle support F, through which the dust and dirt can be easily turned into an opening in the stove or into any proper dust-receptacle. From the top of the bail or handle-supporting piece F, rises the socket G, into which a handle of any desired length may be inserted. The front edge of the bottom B is bent down, as shown at *c*, while a small projection, *d*, is fastened or attached to the centre of the rear of the bottom. It will be observed that the combined effect of the projection *d* and bent front edges *c* of the bottom B is to render the bottom of the dust-pan self-adjusting, and that the front edge of the pan will always fit close to the carpet or floor, since the projection *d* keeps the rear of the bottom B above the floor or carpet, and the front edge *c* always down close to the carpet or floor.

The operation is as follows: The pan is dropped or placed upon the floor or carpet in any convenient place, and the dirt or dust upon the floor or carpet swept into it, which can be easily and conveniently done without stooping more than is necessary in ordinary sweeping. The sweeper now takes hold of the handle, which is to be inserted in the socket G, and lifts the pan and carries it to some convenient place and empties the dirt and dust from the rear of the pan through the opening E, back of the bail.

The dust and dirt can be emptied from my improved dust-pan in a much more convenient and secure manner than from the common dust-pan. Again, the fatigue and labor of stooping down and brushing the dust and dirt into the pan, necessary when the common pan are used, are entirely obviated by the use of my improved dust-pan.

Having described my improvements, what I claim as my invention, and desire to secure by Letters Patent, is—

A dust-pan in which the bottom B, converging sides C, and inclined back D are arranged as described and shown in the accompanying drawings.

ALDEN BRIGHAM.
